NEW YORK; SAID GARFINKEL ASSIGNOR TO SAID GOLDSTEIN

MACHINE FOR PACKAGING STRAWS AND THE LIKE

Application filed May 20, 1927. Serial No. 193,013.

This invention is a machine for packaging drinking straws and the like.

The machine takes a ribbon of paper, forms it into a tube, inserts two straws into the tube, and then crimps both ends of the tube closed, all of these operations being entirely automatic.

In machines of this character heretofore used, the mechanism for selecting two, and only two straws, has been unduly complicated.

One of the important objects of this invention is an improvement and simplification of the mechanism for selecting and feeding two straws at a time. More specifically, straws from a hopper are fed in close parallelism along a channel or passage under a slight but firm pressure; the mouth of this passage opens onto a rotary straw carrying drum or wheel, having in it a number of parallel slots, the depth of which considered radially is about equal to twice the diameter of a straw. The result of this is that as this straw carrying drum moves past the delivery channel, two straws will be pushed into the given recess. This will fill it up, and prevent any further delivery of straws until the next empty recess comes opposite the delivery mouth. The straws from this carrying drum are pushed lengthwise from it into a tube, formed by another part of the machine, after which both ends of the tube are crimped closed simultaneously.

In the art, it has sometimes been customary to crimp one end of the tube closed, then to insert the straw, and then to crimp the other end of the tube closed. According to this invention, the straws are put into the tube while both ends are open, and then both ends closed by crimping them simultaneously.

Another improvement effected by this invention is in connection with the insertion of the straws. A pair of fingers, just before the straws are inserted, grip the far end of the tube, one of the fingers being on the inside and the other being on the outside of the tube, and moves the tube lengthwise towards the straws; after the straws have

been inserted, these two fingers move backwardly, pulling the filled tube back into normal position and then releasing it.

It is also customary in this art to print on the paper strip from which the tube is made. One of the objects of this invention is to provide improved positioning and adjusting means for this printing mechanism.

The invention also comprises improvements in various structural details and arrangement of parts, which are more specifically described in connection with the accompanying drawings illustrating the preferred embodiment of the invention. It should be understood that the disclosure here is illustrative of the present preferred form of the invention, and that it may be carried out in other ways.

In the drawings,

Fig. 1 is a top plan view;

Fig. 2 is a side view, looking from that part of the machine shown at the lower edge of the sheet showing Fig. 1;

Fig. 3 is an enlarged vertical section on the line 3—3, Fig. 1, looking in the direction of the arrows;

Fig. 4 is an end view, taken from the left-hand end of the machine, Fig. 1, looking to the right;

Fig. 5 is a section on an enlarged scale, taken on the line 5—5 of Fig. 1, showing certain details of the feeding mechanism;

Fig. 6 is a section on an enlarged scale taken on the line 6—6 of Fig. 1, showing certain details of the mechanism for moving the tube to and from loading position;

Figs. 7 to 10 inclusive show the finger mechanism for moving the tube to and from loading position, Figs. 7 and 8 being plan views and Figs. 9 and 10 being side elevations of Figs. 7 and 8.

Figs. 11 and 12 are longitudinal and transverse sections, respectively, showing the tube cutting mechanism.

Figs. 13 and 14 show details of the printing roller.

Fig. 15 is a sectional view, and Fig. 16 is a perspective view, of a modification of a

detail, for inserting one straw, instead of two.

Referring now to these drawings, in which similar reference characters indicate similar parts, the machine comprises a bed plate 1, supported on one end of the bed plate, by bolts 3 is a vertically disposed supporting plate 4, having on it a bracket 5 for supporting a roll of paper 6. The ribbon 7 of paper, in this instance a little over an inch wide, is guided over a tensioning roller 8 and then between an impression roll 9 and a printing roll 10, which prints suitable indicia on the paper ribbon and then passes over a plurality of guide rollers 11, 12, 13, 14, 15 and 16. Some of these rollers, as 15, for example, may be mounted on a pivoted bracket 17, having an arm 18 connected to a spring 19, for exerting a proper tension on the paper ribbon. Others of these rolls, as 16, may be mounted on an arm 20 which is variably positionable about the pivot 21, acting to take up or let out the paper strip so that it will be properly positioned with respect to the crimping and cutting mechanism, presently to be described.

Coming back to the printing roll 10, and referring particularly to Figures 13 and 14, this roll is mounted on a shaft 22, and is longitudinally positionable on that shaft by means of a nut 23 on one side of the printing roll 10 and a spring 24 on the other side, the spring bearing against the mounting plate 4. It will be apparent that by rotating the nut 23 in either direction, the printing roll 10 may be moved along its shaft and so accurately positioned with respect to the paper ribbon 7. Ink from the ink fountain 25 is carried to the printing roll 10 through the usual arrangement of rolls 26 and 27. The shaft 22 is provided with a bevel gear 28 meshing with another bevel gear 29 on the shaft 30, which is driven through spur gears 31 and 32, the gear 32 being on a driven shaft 33.

The ribbon of paper 7, after leaving the roller 16, passes to the tube forming mechanism, of any desired known type, comprising a member 35 for curling up the paper ribbon and guide members 36 for overlapping the longitudinal edges of the strip. The paper continues under the rotating crimping roll 37, a cooperating rod 38 extending down the tube underneath crimping roll 37. This mechanism forms a continuous paper tube.

The next step is to cut this paper tube into proper lengths. This is effected by scissors mechanism comprising pivoted blades 40 and 40' mounted on a shaft 41, one of the blades 40 being rigid with an arm 42 and the other 40' being rigid with an arm 43, these arms being connected by a spring 44. These arms 45 are normally held separated in the position

shown in Figure 12 by a pair of rollers 45 mounted on a vertically reciprocable slide 46 which is slotted at 47 and is guided by pins 48 working in these slots, the pins being mounted in a vertical standard 49. A cam 50 on the continuously driven shaft 51 bears against the lower end 52 of this vertically reciprocating slide 46 and moves it up and down. It will be apparent that when the slide 46 moves down, the spring 44 will pull the cutting blades 40 together for the cutting operation.

Since the paper tube, formed by the described crimping roll 37, is moving continuously, it is necessary that the scissors mechanism, when it is cutting the tube, be moved in the same direction at the same speed, in order to prevent buckling or pulling of the relatively fragile paper tube. This longitudinal movement of the scissors is effected by mounting the entire scissors mechanism on a reciprocable guideway comprising a horizontal member 49', connected to the vertical member 49, member 49' sliding through guides 53 and 54. A spring 55 connected to a lug 56 on 52 and to a fixed lug 57, urges 49' to the right, Figure 11. Slide 49' is provided with a downwardly extending portion 58 which bears against a cam mounted on the continuously driven shaft 95 60.

The described mechanism operates as follows:

Cam 59 forces the slide 49' and standard 49 to the left, at a rate about equal to the rate of travel of the paper tube, the scissors 40 and 40' of course moving likewise. During this longitudinal movement of the scissors, the cam 50 raises the slide 46, closing the scissors and cutting the tube. Immediately thereafter, the cam 50 releases the slide 46, the spring 44 pushing the slide down, thereby immediately opening the scissors again. By this time, member 58 is coming against the low part of cam 59 and spring 55 pulls the slide 49' to the right, completing the cycle and positioning the parts for the next cutting operation.

The continuous paper tube formed by the crimping roll 37 passes to the left, Figure 1, into a tube carrying drum 65, which is rotated counterclockwise, Figure 3, with an intermittent or step by step movement. The tube carrying drum 65 is provided with a plurality of longitudinally extending parallel outwardly opening grooves 66, into which the continuously formed tube from the crimping roll passes. After a length of tube equal to the length of the finished tube has passed into one of the grooves 66 of this drum, the cutting mechanism just described comes into action and cuts the tube, thus leaving an open-ended paper tube 67 in place on the drum 65, as shown in Fig. 2. A curved guide plate 68 is placed over the 130

drum 65 for holding the tubes 67 in their respective grooves. The paper tubes 67 are now in position to receive two straws at a time from the straw feeding mechanism, 5 which will now be described, reference being made particularly to Figures 1, 3 and 5.

The straws 70 are carried in a hopper 71, the walls of which merge into parallel upper and lower plates 72 and 73, spaced apart 10 a distance slightly greater than the diameter of one straw, so that this passage 74 receives a plurality of straws in single file and in contacting parallel relation. As oscillating plate or arm 75 positioned inside the hopper 15 and pivoted on a shaft 76, swings back and forth slowly and serves to feed the straws into the described passage 74. The shaft 76 is provided with an arm 77 on the outside of the hopper, the lower end of the arm 77 20 bearing against a cam 78 on the continuously driven shaft 79, thereby oscillating the arm 77 and shaft 76.

A light but continuous and steady pressure is exerted on the straws in the passage 25 74 by means of continuously rotating brushes 80 mounted on a shaft 81 which shaft is provided with a pulley 82 driven by a belt 83. The wall 71 of the hopper and part of the wall 72 of passage 74 are cut away as 30 indicated so that the bristles of the brush, which is rotated clockwise, Figure 5, are continuously pushing against the straws 70 and pushing them lightly but firmly along the passage 74.

The passage 74 has a delivery opening 84 which opens adjacent the periphery of a straw carrying drum 85 mounted on the shaft 86. This straw carrying drum is provided with a plurality of longitudinally extending parallel straw receiving grooves 87. These grooves 87 are laterally elongated in a radial direction an amount about equal to twice the diameter of the straw, the result of which is that after two straws are positioned in one of these grooves, the groove will be full and it will not take any more straws, whereby each groove will take two and only two straws. The straw carrying drum 85 is rotated counterclockwise, Figure 40 5. A guide plate 88 is positioned as shown for keeping the straws in their grooves. The belt 83 passes over a guide pulley 90 and around a pulley 91 mounted on a shaft 92 which in turn is provided with a pulley 93 55 driven by another belt 94 from a pulley wheel 95 on the driven shaft 33.

The pair of straws in the grooves of the straw carrying drum 85 are pushed endwise from their grooves toward the empty. 60 paper tubes 67 in the tube carrying drum 65, by a reciprocating pusher rod 96, which is connected to a reciprocating rack bar 97 which is engaged by an oscillating spur gear 98, mounted on a shaft 99, in turn provided with a small spur gear 100 which

meshes with an arcuate rack 101, mounted on a pivot 102 and connected to an arm 103, the other end of which is pivoted at 104 to a disk 105 mounted on the continuously driven shaft 60, already mentioned. From 70 this mechanism it will be evident that the rod 96 is reciprocated for the purpose described.

Near the left-hand side of the straw carrying drum 85 is an L-shaped bracket 110 having a hollow guide tube 111, pointed toward the paper tubes on the tube carrier 65. The bracket has a suitable hole therethrough registering with the passage in the guide 111. The empty tubes 67 are moved to the right 75 80 on the guide 111, and while on the guide, the rod 96 pushes two straws from the straw carrying drum 85 into the tube. The mechanism for pushing the tubes onto the guide 111 and restoring them to their original 85 position, will now be described, particular reference being made to Figs. 1, 2 and 7 to 10 inclusive.

Mounted on the bracket 115 is a hollow bearing member 116 having a slot 117; 90 mounted to reciprocate in the bearing is a rod 118 having a pin 119 projecting up through the slot 117 into engagement with an oscillating arm 120. Arm 120 is fixed to a vertically positioned shaft 121, the lower 95 end of which shaft has a rearward extension 122 which is provided with a roller 123 bearing against a side cam 124 fixed to rotate on shaft 33. A spring 125 holds the roller 123 against the cam 124. The action of the 100 cam is to give an oscillating movement to the arm 120 and to the member 118.

On the end of the shaft 118 is an offset 126 having a fixed finger 127 projecting therefrom. Pivoted at 128 on member 118 105 129 is a movable clamping device 129 having a clamping finger 130 at one end, a spring 131 serving to urge finger 130 toward finger 127.

On the other end of the clamping member 129 is an upwardly extending pin 132 which is adapted to bear against the inclined cam surface 133 on the member 134, thereby to cause finger 130 to move away from finger 127, as shown in Fig. 7. 110

The mechanism just described operates as follows:

With the parts as shown in Fig. 7, arm 120 starts to move to the right, finger 127 120 entering one of the paper tubes 67. As soon as finger 132 rides off the cam surface 133, spring 131 pulls the clamp 129 to the position shown in Fig. 8, whereupon the paper tube is gripped between the spring fingers 130 and 127, and moved to the right an amount sufficient to push it on the guide 111. After the straws have been inserted by the pusher rod 96, arm 120 swings back, fingers 127 and 130 still gripping the paper tube, 125 thereby pulling it back to normal position 130

on the drum 65. By the time the tube is back in normal position on the drum 65, cam 133 moves the parts back to the position of Fig. 7, thereby releasing the tube.

- 5 The paper tube now contains two straws and is still open at both ends. Both ends of the tube are crimped closed by two pairs of crimping rollers, the inner pair being indicated at 136 and the outer pair at 137.
- 10 The inner pair of crimping rollers 136 are mounted on brackets 138 pivoted at 139; rollers 136 are urged toward their companion rollers 137 by springs 140, connected to the lower end of brackets 138, see Fig. 4.
- 15 The outer set of crimping rollers 137 is mounted on a shaft 141, which is positively driven by a gear wheel 142 meshing with the gear wheel 143. Thus the two open ends of the filled tube are crimped closed simultaneously.

In order to insure that the paper tube, now filled and having its ends closed, shall drop out of its groove in the drum 75, there is provided near each end of the drum 65

25 a pair of arms 145 which oscillate up and down. These arms are pivoted at 146 and have an extension 147 bearing against a cam 148 on shaft 33, which serves to move them up and down thereby to dislodge each

30 filled tube from its groove in the drum 65.

The straw carrying drum 85 and the tube carrying drum 65 are operated with a step by step movement. This step by step movement is given to drum 85 through a ratchet 35 150 mounted on shaft 86, the ratchet being actuated by a pawl 151 which is mounted on an arm 152 journaled on shaft 86; arm 152 is oscillated by a link 153 connected to lever 154 pivoted at 155, the lever being rocked by a cam 156 on shaft 33, whereby the shaft 86 and its drum will be intermittently driven. For properly centering the drum 85 at the end of its movement, there is provided a wheel 160, fixed on shaft 86, which has in its periphery a plurality of semi-circular depressions 161, into which a spring pressed roller 162 snaps. The purpose of this positioning means is to insure that the straws to be ejected by rod 96 are directly in line

50 with the guide member 111.

The tube carrying drum 65 is mounted on a shaft 165 supported in a suitable standard 166 and has a step by step movement imparted to it through a ratchet 167 (see Fig. 5) secured on shaft 165, the ratchet being actuated by a spring pawl 168 mounted on the arm 169 pivoted at 170, the other end of which engages with a cam 171 on shaft 33, whereby an up and down movement is given

60 to the pawl 168.

For the purpose of accurately centering the drum 65 after each actuation, shaft 165 is provided with a wheel 172, which has in its periphery a plurality of semi-circular depressions into which a spring pressed roller

173 snaps, thereby accurately positioning the drum 65. Roller 173 is mounted on a pivoted arm 173'.

Power is applied to the machine through fast and loose pulleys 174 and 175 mounted on shaft 176, which is preferably provided with a fly-wheel 177. Shaft 176 has a bevel gear 178 which drives another bevel gear 179 on shaft 51, already mentioned, on which is mounted the disk 181.

The crimping roll 37 is driven by shaft 182 which is in turn driven by a chain of gears 183 driven from a shaft 184, which shaft is driven from a disk 185.

Shaft 60, already mentioned, which gives a longitudinal movement to the scissors mechanism, is driven from a disk 187.

Shaft 33, already described, is provided with a bevel gear 188, driven by another bevel gear 189 which is in turn driven by a disk 190.

In order properly to synchronize the movements of the four driving disks 181, 185, 187 and 190 and their respective shafts, these disks are interconnected by means of a four-sided driving frame, leg 191 of which connects disks 181 and 185; leg 192 connects disks 185 and 190; leg 193 connects disks 190 and 187; and leg 194 connects disks 187 and 181.

The operation of the machine may be summarized as follows:

The ribbon or paper 7 is printed by the printing roller 10 and is crimped into a continuous tube by the crimping rollers 37 and thereafter passed directly to the grooves in the tube carrying drum 65. As soon as a suitable length of tube has passed the scissors 40, 40', the scissors are actuated to cut off a length of tube. The drum 65 is then moved by its ratchet to bring an empty groove in line for receiving another empty tube. Meanwhile, each of the straw receiving grooves in the straw drum 85 are being filled with two and only two straws. The tube moving mechanism of Figs. 7 and 8 takes one end of the paper tube and moves it to the right, Fig. 2, onto the guide 111. Then the rod 96 pushes two straws into the paper tube, after which the tube is pulled back to its normal position on the drum 65. This drum carries the filled, but still open-ended tubes between the two pairs of crimping rollers 136 and 137, which crimp both ends closed simultaneously. The finished tubes are then dislodged by the arm 145 into any suitable delivery means shown in Fig. 1 at 196.

It may be desirable, under certain conditions, to insert only one straw into the tube, instead of two. A modification for this purpose is shown in Figs. 15 and 16. A bar 195, having apertures 196 in its end, is bolted by bolts 197 passing through apertures 196, to the standard 198. This bar carries a pair

of vertically disposed fingers 199, about equal in thickness to the diameter of one straw, positioned alongside the straw carrying drum 85, in such a position as to allow 5 only one straw 70 to pass into each straw carrying groove 87. This single straw is pushed by the reciprocating rod 96 into a paper tube 67, as has been described.

While the preferred form of the invention 10 has been illustrated in some detail, it should be understood that the disclosure is illustrative and not restrictive of the invention and that it may be carried out in other ways, as falling within the scope of the following 15 claims.

We claim as our invention:

1. In a machine for packaging straws and the like, the combination of a feed hopper, a straw-carrying drum, means for intermittently rotating the drum, a channel leading 20 from the hopper to the drum, in which the straws are maintained side by side in parallel relation, the channel having a delivery opening next the drum, means for pushing the straws along said channel and reciprocable means limited in its movement to a rectilinear path, for pushing the straws endwise out of the drum, during the periods when the drum is stationary.

2. In a machine for packaging straws and the like, the combination of a feed hopper, a straw-carrying drum, means for intermittently rotating the drum, a channel leading 35 from the hopper to the drum, in which the straws are maintained side by side in parallel relation, the channel having a delivery opening next the drum, a rotating brush for pushing the straws along said channel and reciprocable means limited in its movement to a rectilinear path, for pushing the straws 40 endwise out of the drum, during the periods when the drum is stationary.

3. In a machine for packing straws and the like, the combination of a feed hopper, a straw-carrying drum, means for intermittently rotating the drum, a channel leading 45 from the hopper to the drum, movable means in the hopper for facilitating the movement of the straws into said channel, in which the straws are maintained side by side in parallel relation, the channel having a delivery opening next the drum, means for pushing the straws along said channel and reciprocable means limited in its movement to a rectilinear path, for pushing the straws 55 endwise out of the drum, during the periods when the drum is stationary.

4. In a machine for packing straws and the like, the combination of a feed hopper, 60 a straw-carrying drum, means for intermittently rotating the drum, a channel leading from the hopper to the drum, movable means in the hopper for facilitating the movement of the straws into said channel, in which 65 the straws are maintained side by side in

parallel relation, the channel having a delivery opening next the drum, a rotating brush for pushing the straws along said channel and reciprocable means limited in its movement to a rectilinear path, for pushing the straws endwise out of the drum, during the periods when the drum is stationary.

5. In a machine for packaging straws and the like, the combination of a straw carrying drum, having in its periphery a plurality of parallel, longitudinally extending straw-receiving grooves, each groove being large enough to receive two, and only two, straws, means for presenting at the periphery of said drum a plurality of straws in 80 continuous succession, parallel to said grooves, means for intermittently rotating said drum and reciprocable means limited in its movement to a rectilinear path, for pushing two straws at a time endwise out 85 of the drum, this means being operable only during the periods when the drum is stationary.

6. In a machine for packaging straws and the like, the combination of a straw carrying drum, having in its periphery a plurality of parallel, longitudinally extending straw-receiving grooves, each groove being large enough to receive two, and only two, straws, a straw delivering channel in which 95 the straws are maintained in parallel and contacting relation, for delivering a continuous succession of straws to the grooves in the straw-carrying drum, means for rotating said drum intermittently and reciprocable means limited in its movement to a rectilinear path, for pushing two straws at a time endwise out of the drum, this means 100 being operable only during the periods when the drum is stationary.

7. In a machine for packaging straws and the like, the combination of a straw carrying drum, having in its periphery a plurality of parallel, longitudinally extending straw-receiving grooves, each groove being large enough to receive two, and only two, straws, a straw delivering channel in which 110 the straws are maintained in parallel and contacting relation, means for exerting a pressure on the straws in the channel for moving them along, said straw delivering channel serving to deliver straws to, and fill, said straw receiving grooves, a tube carrying drum having an axis parallel to but laterally displaced from the axis of the straw carrying drum, means for intermittently rotating both said drums in unison, and means, operable when the drums are stationary, for pushing two straws from the straw carrying drum into a tube on 120 the tube carrying drum.

8. In a machine for packaging straws and the like, the combination of a straw carrying drum, having a plurality of longitudinally extending, laterally elongated parallel, 130

peripheral straw receiving grooves, the depth of a given groove being about equal to the diameter of two straws, means for maintaining a plurality of straws in parallel and contacting relationship, and for delivering the straws in single file and continuously to said straw receiving grooves, a tube carrying drum having an axis parallel to but laterally displaced from the axis of the straw carrying drum, means for intermittently rotating both said drums in unison, and means, operable when the drums are stationary, for pushing two straws from the straw carrying drum into a tube on the tube carrying drum.

9. In a machine for packaging straws and the like, the combination of a straw receiving drum, having in its periphery a plurality of parallel, outwardly opening grooves, the grooves being laterally widened, in a radial direction, an amount sufficient for receiving two, and only two, straws, means for continuously feeding a plurality of straws while in parallel and contacting relationship, into said straw receiving grooves a tube carrying drum having an axis parallel to, but laterally displaced from the axis of the straw carrying drum, means for inserting a straw into a tube, and means for moving the drums and straw inserting means intermittently.

10. In a machine for packaging straws and the like, the combination of a straw receiving drum, having in its periphery a plurality of parallel, outwardly opening grooves, the grooves being laterally widened, in a radial direction, an amount sufficient for receiving two, and only two, straws, a straw delivering channel for delivering a continuous succession of straws, in parallel, contacting relationship, to said grooves, means for exerting a steady pressure on the straws in the channel for moving them toward said straw receiving drum, a tube carrying drum having an axis parallel to, but laterally displaced from the axis of the straw carrying drum, means for inserting a straw into a tube, and means for moving the drums and straw inserting means intermittently.

11. In a machine for packaging straws and the like, the combination of a straw receiving drum, having in its periphery a plurality of parallel, outwardly opening grooves, the grooves being laterally widened, in a radial direction, an amount sufficient for receiving two, and only two, straws, a straw delivering channel for delivering a continuous succession of straws in parallel, contacting relationship, to said grooves, a rotating brush for exerting a steady pressure on the straws for moving them along said channel, a tube carrying drum having an axis parallel to, but laterally displaced from the axis of the straw carrying drum, means for inserting a straw into a tube,

and means for moving the drums and straw inserting means intermittently.

12. In a machine for packaging straws and the like, the combination of a tube carrying drum, provided with a plurality of parallel, tube-receiving grooves, a straw receiving drum near one end of the tube carrying drum, means, having a finger insertable into one end of the tube, for moving the tube toward the straw receiving drum for receiving a straw, and thereafter pulling the tube back to its former position.

13. In a machine for packaging straws and the like, the combination of a straw carrying drum provided with parallel straw holding grooves, a tube carrying drum, mounted on an axis parallel to but displaced from the axis of the straw carrying drum, means for intermittently rotating the drums in unison, reciprocable means, limited in its movement to a rectilinear path, and operable when both drums are stationary, for transferring straws from the straw carrying drum and putting them into the tubes on the tube carrying drum.

14. In a machine for packaging straws and the like, the combination of a straw carrying drum provided with parallel straw holding grooves, a tube carrying drum, mounted on an axis parallel to but displaced from the axis of the straw carrying drum, and means operating intermittently, to push a straw into a tube on the tube-carrying drum.

15. In a machine for packaging straws and the like, the combination of a straw carrying drum provided with parallel straw holding grooves, a tube carrying drum, mounted on an axis parallel to but displaced from the axis of the straw carrying drum, and means operating intermittently, to push a straw into a tube on the tube-carrying drum, including means for moving a tube toward a straw, and thereafter retracting it.

16. In a machine for packaging straws and the like, the combination of a straw carrying drum provided with parallel straw holding grooves, a tube carrying drum, mounted on an axis parallel to but displaced from the axis of the straw carrying drum and reciprocating means for transferring a straw from the straw-carrying drum and inserting it into a tube, including mechanism for moving a tube toward a straw and retracting it after the insertion of a straw.

17. In a machine for packaging straws and the like, the combination of a straw carrying drum provided with parallel straw holding grooves, a tube carrying drum, mounted on an axis parallel to be displaced from the axis of the straw carrying drum, and means for transferring the straws from the straw carrying drum and inserting them

into the tubes, including a guide member between the two drums, and mechanism for placing a tube on said guide member before a straw is inserted and retracting the tube after a straw has been inserted.

- 5 18. In a machine for packaging straws and the like, the combination of a grooved, rotatable straw carrying drum, means for supplying straws to the grooves in said drum, a grooved, rotatable tube carrying drum, rotating on an axis parallel to but displaced from the axis of the straw carrying drum, means for supplying tubes to the grooves in the tube carrying drum, means for rotating the drums intermittently in opposite directions, and means operable when the drums are stationary, for pushing straws from the straw carrying drum into the tubes on the tube carrying drum.
- 10 19. In a machine for packaging straws and the like, the combination of a grooved, rotatable straw carrying drum, means for supplying straws to the grooves in said drum, a grooved, rotatable tube carrying drum, rotating on an axis parallel to but displaced from the axis of the straw carrying drum, means for moving the tubes endwise, in a direction parallel to the axis of the tube carrying drum, for placing them 15 in the grooves in said drum, means for rotating the drums intermittently in opposite directions, and means operable when the drums are stationary, for transferring the straws into the tubes.
- 20 20. In a machine for packaging straws and the like, the combination of a grooved, rotatable straw carrying drum, means for supplying straws to the grooves in said drum, a grooved, rotatable tube carrying drum, rotating on an axis parallel to but displaced from the axis of the straw carrying drum, means for moving the tubes endwise, in a direction parallel to the axis of the tube carrying drum, for placing them 25 in the grooves in said drum, means for rotating the drums intermittently in opposite directions, and means operable when the drums are stationary, for transferring the straws into the tubes.
